UNITED STATES PATENT OFFICE.

JOSEPH KRAUS, OF ANACONDA, MONTANA.

FILTER-MASS WASHER.

1,139,776.

Specification of Letters Patent. Patented May 18, 1915.

Continuation of application Serial No. 566,991, filed June 15, 1910. This application filed June 5, 1913. Serial No. 771,910.

To all whom it may concern:

Be it known that I, JOSEPH KRAUS, a citizen of the United States, residing at Anaconda, in the county of Deerlodge, State of Montana, have invented certain new and useful Improvements in Filter-Mass Washers; and I do hereby declare the following to be a full, clear, and exact description of the invention, such as will enable others skilled in the art to which it appertains to make and use the same.

This invention relates to filter mass washers and more especially to an apparatus of this character for removing deteriorated waste and other impurities from a filter mass, and is an improvement on my application of similar nature filed June 15, 1910, S. N. 566,991.

Another object of the invention is to provide efficient means for thoroughly mixing the water and mass composed of pulp and cotton, and for continuously washing the mass and removing the impurities therefrom, after the beer has been filtered therethrough, whereby a desirable and comparatively pure product is obtained.

A further object of the invention is to provide a device of this character which will occupy a small amount of space and which may be readily set up and cleaned when desired, at the same time being cheap and economical to manufacture.

Further objects and advantages will be apparent from the following description, and it will be understood that changes in the specific structure shown and described may be made within the scope of the claims without departing from the spirit of the invention.

In the drawings: Figure 1 is a side elevation of my improved apparatus, partly in section to more clearly illustrate the same. Fig. 2 is a plan view of the device. Fig. 3 is a detail sectional view of a sieve used in connection with my apparatus. Fig. 4 is an end view of the sieve. Fig. 5 is a detail view showing the manner of uniting the stationary and revolving parts of the operating shaft for the tank. Fig. 6 is a side elevation of a fragment of the driving gear.

Referring more particularly to the accompanying drawings in which similar characters of reference designate corresponding parts throughout, 10 indicates a suitable vertical tank, preferably construct-

ed of metal and provided with a cover 11 which is fitted over the upper end of the tank or otherwise secured thereto, said tank being supported by means of suitable legs 13 which are attached to its inclined bottom 12 and which rest upon the base member 14. The tank is provided centrally with a vertical hollow shaft 15, the lower end of which is received by and rigidly secured to a ground bearing 16 having a tapered lower face disposed and supported upon a base arch 17 having suitable openings therethrough to allow the escape of the mass under the action of suction caused by the continual flow of water or steam. The lower end of the shaft 15 stops short of a stationary tube 18 which is carried by the base arch 17 and securely held from rotation. Said hollow shaft 15 is provided with a plurality of bent pipes 19 disposed upon the shaft and secured thereto in stepped relation by means of sleeves 20 at spaced distances from the lower end of the tank and below the cover thereof. The pipes 19 have their free ends 21 turned downwardly and bent in a direction opposite to the rotation of the shaft 15, as will be clearly apparent by referring to the drawings.

The stationary tube 18 is disposed through the sleeve 22 which is adapted to form and surround a space through which the mass may be drawn, and which has attached thereto the three way coupling 23 to the bottom portion of which extends the stationary tube 18 where it is detachably fitted for communication with the supply pipe 24.

By means of the supply pipe 24 water or steam is admitted through the hollow shaft 15 and through the pipes 19, previously mentioned, it being understood that the water or steam applied thereto will from the pressure thereof shoot downwardly from the down turned ends 21 of said pipes 19 so as to thoroughly mix the water and filter mass.

As will be understood the supply pipe 24 turns upwardly along one side of the tank and is provided at its upper end with a valve 25 and a horizontal pipe 26 is provided with suitable steam inlet 27, the opposite end of said horizontal pipe having a similar valve 28 and a downwardly extending portion 29 forming an injector 30. In order to control the passage of said mass through the pipe 31 I provide a suitable

valve 32 and said pipe is further provided with valved extensions 33 whereby said pipe may be properly drained for the purpose of cleaning the same. Pipes 34 are also disposed in communication with the supply pipes 24 and 29 a short distance from their upper ends where the latter are provided with injectors 30. The horizontal connecting pipe 35 of said upright pipe sections 34 is provided with suitable controlling valves 36 and has a suitable inlet 37 for supplying water thereto. It will be understood that water may be conveyed from the main or any other suitable source, as well as from the source of supply of the water for making the steam.

The injector 38 is secured in the lower end of the vertical discharge pipe 39 which latter is provided upon its upper end with a suitable nozzle 40 adapted to discharge the filter mass into a revolving cylindrical sieve 41, the injector 30 aiding in this operation said sieve being mounted upon an inclined shaft 42 supported by the bracket arm 43 carried by the cover of the tank. The sieve 41 is arranged parallel with the short horizontal shaft 44, and will later be more fully described. The injector 38 is formed with a restricted spout and the water or steam discharged therefrom will therefore escape under increased pressure to carry the mass upward through the pipe 39 and into the sieve 41.

The sieve 41 is formed with a sheet metal section 44' to receive the mass from the nozzle 40. It will also be understood that the cover is provided with an opening 45 beneath the sieve for discharging the filter mass into the tank and a sprinkler pipe 46 is disposed above the sieve upon a suitable pipe 47 leading from the horizontal connecting water pipe 35, the purpose of this sprinkling pipe being to prevent clogging of the sieve.

When it is desired to remove the mass from the tank 10 the valve 52 is opened, thus allowing the mass to flow from the discharge pipe 39 and tank 10 through the extension 33 to a suitable place.

From the foregoing it will be seen that by my improved apparatus the washing operation can be continually carried on and the waste or other impurities can be drawn off and quickly removed from the mass through which the beer has been filtered, it being understood that the impurities have been previously withheld in the mass when the beer was filtered therethrough. Thus the filter mass may be advantageously used again for filtering beer in clarifying the same, thereby decreasing the cost of manufacture and greatly enhancing the economical value of the present apparatus.

To rotate the sieve 41 a gear 53 is fixed to the shaft 42 and meshes with a gear 54

keyed to the shaft 44, motion being imparted to the shaft 44 by a pulley 55, which is driven by a belt in the usual manner. To the inner end of the shaft 44 is fixed a beveled pinion 56 which meshes with a similar gear 57, said gear being fixed to the upper end of the shaft 15 so as to impart rotary movement thereto during the rotation of the sieve. A combined T and cock 51 is connected to the pipe 39, and serve to remove the mass therefrom when desired. Supported beneath the sieve 41 is a trough 58, for receiving the liquid from the mass as it passes through the sieve to the tank, said trough being provided with a pipe 59 to carry the liquid to a sewer or the like.

In operating this device the valves 49 and 51 are closed and steam admitted through the steam inlet valve 27 which steam is forced through the pipes 26 past the open valves 28 and downwardly through the nozzles 30 and 40. At the same time water is admitted through the pipe 37 and flows downwardly through the pipes 34 into the pipes 24 at a point adjacent the end of the nozzles 30 and 40.

Contact of the steam from the nozzle 40 with the water flowing into the pipe 24 heats the said water and forces the same through the pipe and upwardly through the pipe 18 into the hollow shaft 15 and thence outwardly through the curved pipes 19 and expels the same from the ends thereof so as to cause the shaft 15 to rotate and thoroughly mix the filter mass in the cylinder 10. During this operation the steam from the nozzle 30 heats the water entering the pipe 24 through the pipe 34 and forces the same downwardly and inasmuch as the valves 49 and 51 have been previously closed, the water is forced upwardly through the sleeve 22 into the cylinder 10 and not only prevents the filter mass from clogging in this sleeve, but also provides the cylinder with hot water.

After the filter mass has been thoroughly washed, the valve 49 is opened and the said filter mass suspended in water is forced upwardly by the pressure of the steam from the nozzles 30 and 40 through the pipe 39 and into the sieve 41 from whence the water is expelled and the filter mass again deposited into the cylinder 10 for rewashing. After this rewashing process has been completed, during which time of course the valve 49 has been closed, the valve 51 is opened and the clean filter mass drawn therefrom. It is of course to be understood that by regulating the flow of steam from the nozzles 30 and 40 the temperature of the water may be controlled.

From the foregoing description it may be seen that I have provided a construction wherein the water for washing the filter mass will be heated and forced into the wash-

ing cylinder and wherein the steam which is used to heat the water will at the proper time act to force the filter mass and water in which it is suspended upwardly to the screening device.

5 What is claimed is:—

1. A filter mass washing machine comprising a vertical casing constructed and arranged to contain a filter mass, means to 10 inject water into said casing, a pipe having communication with said casing arranged to convey the filter mass from the bottom to the top thereof, means connected to the said pipe and to the injecting means to supply 15 the said injecting means and pipe with water to simultaneously convey water into the casing and force the filter mass upwardly through the said pipe.

2. A filter mass washing machine comprising a vertical casing, a vertically extending injecting pipe in said casing, a pipe connected to the bottom of the said casing and extending upwardly externally thereof to the top of the casing and constructed and 25 arranged to convey water and filter mass from the bottom of the casing to the top thereof, a water supply pipe connected to the said injecting pipe and to the said conveying pipe, a steam pipe connected to the 30 water supply pipe to inject steam thereinto whereby the temperature of the water will be raised, the water injected into the casing and the filter mass forced upwardly through the conveyer pipe.

3. A filter mass washing machine comprising a casing, a hollow shaft in said casing, a conveyer pipe connected to the lower end of the said casing and extending upwardly to the upper end thereof, a U-

shaped pipe extending into the said conveyer pipe and the said hollow shaft, a steam main located in the bight portion of the said pipe, a second U-shaped pipe having the ends of its legs connected to the legs of the first mentioned U-shaped pipe between the ends thereof to supply the said legs with water, the said pipes being so arranged that when steam and water are conveyed therethrough the temperature of the water will be raised, the hollow shaft supplied with heated water and the filter mass forced upwardly through the conveyer pipe.

4. A filter mass washing machine comprising a casing, a hollow shaft therein, a pipe for conveying the filter mass from said casing connected to the lower end thereof and extending upwardly and emptying into the upper end, a U-shaped pipe having one open end thereof extending into the said conveyer pipe adjacent its connection with the casing and the other end thereof connected to the hollow shaft, a steam main connected to the bight portion of said pipe, nozzles arranged in the legs of the said pipe and extending downwardly, water pipes connected to the legs of the said U-shaped pipe adjacent the ends of the nozzles whereby when steam and water are simultaneously injected into said legs the casing will be supplied with heated water and the filter 70 mass forced upwardly through the conveyer pipe.

In testimony whereof, I affix my signature, in the presence of two witnesses.

JOSEPH KRAUS.
